(57) **CLAIM**

The ornamental design for a T-handle, as shown and described.

DESCRIPTION

FIG. 1 is a top plan view of a T-handle showing our new design;

FIG. 2 is a bottom plan view thereof;

FIG. 3 is a right side elevational view thereof;

FIG. 4 is a left side elevational view thereof;

FIG. 5 is a front elevational view thereof;

FIG. 6 is a rear elevational view thereof;

FIG. 7 is a rear perspective thereof; and,

FIG. 8 is a front perspective view thereof.

The broken lines are for illustrative purpose only and form no part of the claimed design.
